(57) **CLAIM**

The ornamental design for an air delivery tube, as shown and described.

DESCRIPTION

FIG. 1 is a front view of an air delivery tube showing the new design;

FIG. 2 is a perspective view thereof;

FIG. 3 is a left-side view thereof;

FIG. 4 is another perspective view thereof;

FIG. 5 is a right-side view thereof;

FIG. 6 is another perspective view thereof;

FIG. 7 is a back view thereof;

FIG. 8 is a top view thereof;

FIG. 9 is a bottom view thereof; and,

FIG. 10 is another perspective view thereof.
